E. L. PRATT, OF BOSTON, MASSACHUSETTS.

Letters Patent No. 66,387, dated July 2, 1867.

IMPROVEMENT IN BOILER-TUBE SCRAPERS.

The Schedule referred to in these Letters Patent and making part of the same.

TO ALL WHOM IT MAY CONCERN:

Be it known that I, E. L. PRATT, of Boston, in the county of Suffolk, and State of Massachusetts, have invented an improved Boiler-Tube Scraper; and I do hereby declare that the following, taken in connection with the drawings which accompany and form part of this specification, is a description of my invention sufficient to enable those skilled in the art to practise it.

The invention relates to the construction of a scraper for cleaning the tubes of steam boilers, and consists primarily in an arrangement of a series of segmental or sectional scraping-blades around a central rod or spindle made movable longitudinally within the scrapers, which are so arranged with relation to a tube or sleeve through which the rod passes, and with relation to expanding shanks by which they are connected with and hung to a head attached to the sleeve, and to an enlargement formed on the rod, that while they may be introduced into the tube in a contracted or closed form to any depth permitted by the length of the sleeve, they may be expanded so as to bring their scraping edges against the sides of the tube to be cleaned; by driving the rod inwards by a blow or pressure upon the head thereof, and in this expanded position may be drawn from the tube, or reciprocated within it, by longitudinal movement of the sleeve, in such manner as to scrape off all deposits upon the surface of said tube. The shanks at the ends at which the scrapers are fixed or formed are jointed to the head so as to permit a slight rocking motion in each scraping edge, and each is cushioned upon a spring, which bears the scrapers against the surface of the tube, when they are expanded, but allows them to yield somewhat to resisting inequalities or obstructions upon the surface being scraped.

The drawings represent a scraper embodying my invention. A shows a side view of the same, the scraping edges being closed together. B, a central section, said edges being expanded. C, a cross-section through the pins, by which the scrapers are connected to the head. D, a cross-section taken on the line *z z*. *a* denotes a head, having slots *b* on its sides, in which are pivoted, on pins *c*, shanks *d*, having fixed upon or preferably formed, integral with their free ends, segmental blades or scrapers, *e*, the outer edge of each of which is formed with a curve concentric, or approximately concentric, with the inner surface of the tube to be cleaned. The head *a* is screwed or otherwise fastened upon the end of a sleeve, *f*, through which extends a rod, *g*, upon the end of which may be fixed a cap, *h*, and this rod has upon it an enlargement or expander, *i*, as seen at B. Each shank piece *d* has secured to its inner face a long spring, *k*, bending inwardly toward the axis of the rod *g*, and when the blades *e* are contracted or closed together, the springs come up to or nearly into contact with the rod, with the expander *i* drawn just within these bends, as seen at A. In this condition the blades are introduced into a tube, *l*, to be cleaned, and are carried to the rear end thereof, the sleeve *f* being made of requisite length for that purpose. When brought to the point at which the scraping is to commence, the rod *g* is forced inwardly, driving the expander *i* against the springs, and forcing the springs outwardly, thereby expanding the blade *e* and forcing their scraping edges against the inner surface of the tube, the cap *h* arresting the inward movement of the rod, so as to leave the expander *i* against the bends in the springs. If the sleeve *f* be now drawn from the tube, it will be obvious that the blades *e* will draw with them the accumulations of soot, &c., deposited on the inner surface of the tube, cushioning the blades by means of the springs, enabling them to yield to the natural or permanent inequalities in the surface of the tube. The shanks *d* may have springs formed integral with them, or may have their inner surfaces formed with inclines to be acted upon by the enlargement on the rod *g*, but cushioning the shanks upon the springs, as shown, is considered preferable. It is desirable that each blade should be capable of a slight rocking movement in the line of its edge, for which purpose each pivot-hole, *m*, is first made of size to correspond with the diameter of the pin *c*, and the hole is then reamed out at each side towards the centre, as seen at C, thereby enabling the shank, and through it the edge of the blade, to rock as may be necessary to cause it to meet the surface of the tube, the slot *b* being of enough greater width than the thickness of the shank to permit such rocking movement. Each shank with its blade is preferably made of malleable cast iron, forming the two in one piece of metal, rendering the blade much more enduring than if it were fastened upon the shank. Each blade has one part, *n*, below the other part, *o*, to allow the part *o* of the next adjacent blade to shut in under it when the blades are closed together.

Scrapers made, as shown and described, are found very efficient in removing carbon deposits from boiler-

tubes, and are greatly superior to brushes and other devices heretofore used for such purpose, while the instrument is inexpensive as well as enduring, and is very easily manipulated.

When necessary or desirable to contract the blades while they are expanded within the tube, the rod is drawn outwardly, causing the expander to strike the inner ends *of* the shanks, and thereby to draw together the blades, as will be readily understood.

I claim, in combination with a series of scraping-blades arranged as described, a sliding-rod, by movement of which the scraping edges may be expanded or contracted when they are within a tube, substantially as described.

Also, in combination with the blades and their shanks and the movable rod, the springs upon which the shanks are cushioned when the blades are expanded, substantially as set forth.

E. L. PRATT.
